UNITED STATES PATENT OFFICE

153,806

DESIGN FOR A HEDGE TRIMMER

Ivar Jepson, Oak Park, Ill., assignor to Sunbeam Corporation, Chicago, Ill., a corporation of Illinois

Application February 16, 1948, Serial No. 144,522

Term of patent 14 years

(Cl. D22—4)

To all whom it may concern:

Be it known that I, Ivar Jepson, residing at Oak Park, in the county of Cook and State of Illinois, have invented a new, original, and ornamental Design for a Hedge Trimmer, of which the following is a specification, reference being had to the accompanying drawing, forming part thereof.

In the drawing:

Figure 1 is a top plan view of a hedge trimmer with a portion of the cutter broken away, showing my new design;

Figure 2 is a side view of the hedge trimmer with a similar portion of the cutter broken away;

Figure 3 is a perspective view of the hedge trimmer looking at the side opposite from that viewed in Figure 2; and

Figure 4 is a perspective view of the hedge trimmer from an angle between the top and side views shown in Figures 1 and 2.

I claim:

The ornamental design for a hedge trimmer, substantially as shown.

IVAR JEPSON.
